UNITED STATES PATENT OFFICE

161,557

CHILD'S ROLLER SKATE

Albert H. Walker, John A. Walker, and
Richard J. Walker, Alameda, Calif.

Application May 2, 1949, Serial No. 2,388

Term of patent 3½ years

(Cl. D34—14)

To all whom it may concern:

Be it known that we, Albert H. Walker, John A. Walker, and Richard J. Walker, citizens of the United States and residents of the city and county of Alameda, State of California, have invented a new, original, and ornamental Design for a Child's Roller Skate, of which the following is a specification, reference being had to the accompanying drawing, forming part thereof.

Figure 1 is a perspective view of a skate, showing our new design.

Figure 2 is a bottom plan view of the skate.

Figure 3 is a side elevational view of the skate.

We claim:

The ornamental design for a child's roller skate substantially as shown.

ALBERT H. WALKER.
JOHN A. WALKER.
RICHARD J. WALKER.
